(57) **CLAIM**

The ornamental design for a pet bowl stand, as shown and described.

DESCRIPTION

FIG. 1 is a front, right and top perspective view of a pet bowl stand showing my new design;

FIG. 2 is a rear, left and bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a front, right and top perspective view, shown in configuration 2;

FIG. 10 is a rear, left and bottom perspective view, shown in configuration 2;

FIG. 11 is a front view, shown in configuration 2;

FIG. 12 is a rear view, shown in configuration 2;

FIG. 13 is a left view thereof, shown in configuration 2;

FIG. 14 is a right view thereof, shown in configuration 2;

FIG. 15 is a top view thereof, shown in configuration 2;

FIG. 16 is a bottom view thereof, shown in configuration 2;

FIG. 17 is a front, right and top perspective view of the pet bowl stand, shown in configuration 3;

FIG. 18 is a front, right and top perspective view of the pet bowl stand, shown in configuration 4;

FIG. 19 is a front, right and top perspective view of the pet bowl stand, shown in configuration 5;

FIG. 20 is a front, right and top perspective view of the pet bowl stand, shown in configuration 6;

FIG. 21 is a front, right and top perspective view of the pet bowl stand, shown in configuration 7; and,

FIG. 22 is a front, right and top perspective view of the pet bowl stand, shown in configuration 8.
